DESIGN FOR A TEXTILE FABRIC OR THE LIKE

Robert E. Fatherley, Darien, Conn.

Application June 20, 1933. Serial No. 48,466

Term of patent 3½ years

To all whom it may concern:

Be it known that I, ROBERT E. FATHERLEY, a citizen of the United States, residing at Darien, county of Fairfield, Connecticut, have invented a new, original, and ornamental Design for a Textile Fabric or the like, of which the following is a specification, reference being had to the accompanying drawing, forming a part thereof.

The figure is a plan view of a textile fabric showing my new design. The area within the dot and dash lines shows one complete unit of

the design. The repeats are arranged in vertical rows and adjacent vertical rows are one half a complete unit offset so that the angle of the complete unit indicated by letter A corresponds with angle B of one of the repeats in an adjacent vertical row.

I claim:

The ornamental design for a textile fabric or the like as shown and described.

In testimony whereof I have signed this specification.

ROBERT E. FATHERLEY.
